Kelsor Howard

UNITED STATES PATENT OFFICE.

FRED L. MACKENZIE, OF BEVERLY, MASSACHUSETTS, ASSIGNOR TO UNITED SHOE MACHINERY CORPORATION, OF PATERSON, NEW JERSEY, A CORPORATION OF NEW JERSEY.

STOCK-FEEDING MECHANISM.

Application filed May 7, 1919. Serial No. 295,413.

To all whom it may concern:

Be it known that I, FRED L. MACKENZIE, a citizen of the United States, residing at Beverly, in the county of Essex and State of Massachusetts, have invented certain Improvements in Stock-Feeding Mechanisms, of which the following description, in connection with the accompanying drawings, is a specification, like reference characters on the drawings indicating like parts in the several figures.

This invention relates to stock feeding mechanisms and more particularly to means for gripping the stock to prevent movement thereof relatively to the said means at certain predetermined periods in the stock feeding operations.

It is an object of the invention to provide simple and effective means for gripping the stock and more particularly means of the kind described which is readily controllable at the will of the operator to release the stock.

In a well-known type of stock gripping mechanism, a circular or cylindrical member is mounted in a slot in the stock guiding member and is arranged to grip the stock upon attempted movement of the latter in one direction and to permit the stock to pass freely upon movement in the opposite direction. This device has been employed especially in connection with wire working machines and as heretofore constructed has not infrequently given trouble because of the collection of dirt therein necessitating the disassembling of the parts of the device. A more serious objection, however, arises from the lack of means for enabling the operator to control the gripping member so that the wire may be withdrawn in the event it becomes damaged in such a way as to affect adversely the operation of the machine or when it is desired to introduce another reel of wire or substitute wire of a different size or quality. It is a further object of the invention to improve this specific type of mechanism in such manner as to provide a stock gripping device which will not clog and which is manually operable to effect the release of the wire at the will of the operator.

Other objects and features of the invention will be apparent from the following detailed description and will be pointed out in the claims.

In the drawings,

Fig. 1 is a front view of a wire working machine showing one application of the invention, and

Fig. 2 is a perspective view, partly in section, of the illustrative embodiment of the invention.

In the illustrative machine, the wire stock 4 is fed from the reel 6 and through a guideway 7 by feeding mechanism of a well-known type comprising an upper feed roll 8 and a lower co-operating feed roll 10. The first-mentioned roll is secured to a shaft 12 which is oscillated positively, first in one direction and then in the other direction 70 through operative connections with lever 14 which is operated by an arm 16 fixedly attached to a shaft 18 driven from the main shaft of the machine. Pivoted at 20 is a supporting arm 22 for the lower feed roll 10 and the gear wheel 24 which latter is held constantly in mesh with the driven gear wheel 26 on the shaft 12 through the operation of a spring 28. In the operation of the machine the feed rolls 8 and 10 80 are rotated positively to feed the wire stock to the right in Fig. 1 for a definite period of time and then the feed roll is moved backwardly preparatory to the next feeding operation, and during the backward movement 85 of said roll the lower roll 10 is separated from the upper roll to release the wire, this being effected by a plunger 30 which moves into contact at the proper time with an adjustable stop 32 in the supporting arm 90 95 22 so as to rock the said arm on its pivot to carry the lower roll out of engagement with the upper roll. For a more detailed disclosure of the parts thus far described reference should be had to the patent to Borden No. 1,016,930, granted February 13, 1912.

As the feed roll 8 turns backwardly at certain regularly recurring periods there is a tendency to displace the wire 4 through 100 engagement with the moving roll. Hence means are provided for preventing movement of the wire in a direction reverse of the direction of feed. This means in the construction shown comprises wire stock 105 gripping means of which the guideway 7 forms a part, since the lower portion of the guideway provides a surface 34 over which the wire passes and against which it is clamped by a cooperating gripper member 110

preferably in the form of a cylinder 36. For economy in manufacture, the guideway 7 is made of two pieces of which the lower presents the wire supporting and clamping surface as described, and the upper a guiding groove as clearly indicated in Fig. 2 of the drawings. Mounted on the upper member 38 of the guideway 7 by means of a projecting arm 40 is a lever 42. This lever has two angularly related arms 44 and 46, the latter projecting into a slot 48 in the upper member 38 of the guideway and being provided with a bifurcated portion 50 which partly embraces and rotatably receives the cylinder 36. The other arm 44 of the lever 42 is acted upon by spring means which operates to cause the arm 46 of the lever to hold the cylinder yieldingly in contact with the wire. In the construction shown the spring means for operating the lever is found in a spring 52 located under and acting upwardly on the outer end of the arm 44 of the lever. Preferably a casing 54 is provided on the upper member 38 of the guideway for housing said spring. The construction and arrangement are such that the cylinder or roller 36 may be moved to clamp and to unclamp or release the wire. Normally the cylinder or roller is held yieldingly against the wire through the operation of the spring 52. Yet this pressure is not sufficient to interfere with the movement of the wire in the direction of feed, that is, to the right in Figs. 1 and 2. It will be clear upon inspection of these figures that movement of the wire in the direction indicated tends to move the cylinder away from the cooperating clamping surface 34, the cylinder being both rotatably and slidably mounted in the forked end of the member 42, and thus no wire clamping or gripping action takes place during the feed of the wire. But upon attempting to move the wire in the reverse direction the friction between the wire and the cylinder tends to carry the cylinder to the left (in Fig. 2) and thus the wire itself assisted by the spring 52 causing a clamping of the wire between the cylinder and the surface 34 which prevents any reverse movement of the wire. In order to obtain a fine adjustment of the lever 42 and especially of its bifurcated end 50 with respect to the cylinder 36 and the clamping surface 34, the pivot 56 of the lever is provided with an eccentric portion 58 which the barrel or bearing of the lever surrounds, the arrangement being such that rotation of the pivot will raise or lower the end 50 of the lever as desired.

It is thought that the manner of operation of the device has been set forth with sufficient detail in connection with the foregoing description of the structural elements of the device. It may be pointed out in addition,

however, that the wire may be released from the gripping device, so that it may be withdrawn toward the left, simply by pressing downwardly on the arm 44 of the lever. Thus a twisted or damaged end of wire 70 stock may be readily removed. It is necessary, moreover, to remove in this way the remnant end of one reel before introducing the leading end of wire from another reel, so that the occasions when the manual control of the gripping device will prove useful are not infrequent. It is clear also that dirt or foreign substances of any kind are not likely to clog the gripper device working in an open slot and that dirt may be readily removed from the slot 48. Moreover, the substitution of new parts for old may be easily effected simply by removing the pivot 56 which is in the form of a bolt. While the stock gripping device just described is 80 very effective for the purposes described it has the additional advantage over many forms of gripping devices of not marring the surface of soft stock. While the invention is disclosed in connection with a stationary guideway so that the function of the device is that of preventing displacement of the wire stock with respect to a stock feeding mechanism, it is clear that the gripping device may be mounted on or be made 90 a part of a reciprocatory member which may then be employed as a wire feeding device.

Having thus described my invention, what I claim as new and desire to secure by Letters Patent of the United States is:

1. In a machine of the class described, wire gripping means comprising a support for the wire, a member mounted at one side of the support and having a bifurcated end, and a cylinder freely slidable and rotatable 105 within the bifurcated end of the member and arranged to be held by said member in contact with the wire to press the same against the support.

2. In a machine of the class described, wire gripping means comprising a support for the wire, a cylinder arranged in engagement with the wire for pressing the same against the support, a member having a forked end arranged to engage the cylindrical surface of the cylinder to control the cylinder, and means for causing the member to press the cylinder against the wire.

3. In a machine of the class described, wire gripping means comprising a support for the wire, a member mounted at one side of the support, a cylinder controlled by said member and arranged to contact with the wire on the side opposite the support, means for acting yieldingly on the member 120 to cause the cylinder to be yieldingly pressed against the wire, and means for adjusting the member toward and from the wire support.

4. In a machine of the class described,

wire gripping means comprising a guide-way for the wire having a slot therein exposing the wire, a lever having one end projecting into said slot, means mounted for free bodily movement in the end of the lever and controlled by said end of the lever for gripping the wire, and means for yieldingly pressing the end of the lever into said slot.

5. In a machine of the class described, 10 wire gripping means comprising a support for the wire, a lever mounted at one side of the support, means controlled by the lever for gripping the wire against the support, means for adjusting the lever toward and from the support for the wire, and means for yieldingly pressing the second-mentioned means against the wire.
6. In a machine of the class described, 15 wire gripping means comprising a support for the wire, a lever mounted at one side

of the support, an eccentric for adjusting said lever toward and from said support, a cylinder for clamping the wire on the support and arranged to be controlled by said lever, and a spring operative to press the cylinder yieldingly against the wire on the support.

7. Mechanism for gripping wire stock comprising a support for the wire, a cylinder of metal or other suitable substance, 20 a member having a forked end arranged to engage the cylindrical surface of the cylinder to press the same against the wire, and a spring for moving the member in the direction to cause the cylinder to grip the 25 wire.

In testimony whereof I have signed my name to this specification.

FRED L. MACKENZIE.
